UNITED STATES PATENT OFFICE.

CHARLES SELDEN, OF BALTIMORE, MARYLAND, ASSIGNOR TO THOMAS M. KING, OF SAME PLACE, AND THE WESTINGHOUSE AIR BRAKE COMPANY, OF WILMERDING, PENNSYLVANIA.

RAILWAY-BRAKE.

SPECIFICATION forming part of Letters Patent No. 531,653, dated January 1, 1895.

Application filed May 20, 1887. Serial No. 238,889. (No model.)

To all whom it may concern:

Be it known that I, CHARLES SELDEN, a citizen of the United States, and a resident of Baltimore, in the State of Maryland, have invented a certain new and useful Railway-Brake, of which the following is a specification.

My invention relates to means for controlling the action of brakes that are operated by the pressure of air, steam or other fluid.

The invention is designed more especially for application to railway brakes in which air pressure is employed for operating a piston head mechanically connected with the brake.

15 The object of the invention is to provide a means whereby the power of the compressed air or other fluid upon the brakes may be regulated, and whereby the engineer may have control of the pressure and apply the 20 brakes gradually by reason of the control which he has over the action of a valve or valves located in immediate proximity to the brake cylinder, and also to provide a means whereby, when the brake has been applied to 25 the full extent of the pressure contained within the cylinder and connected passages at the time of the application the pressure may be still further augmented by direct pressure from the air supply.

30 In an application for patent filed by me April 2, 1883, Serial No. 90,415, a method of controlling the action of brakes is shown, and in other patents issued to me April 12, 1887, Nos. 361,089 and 361,090, I have shown the 35 desirability of, and the necessity for, devices of this character, electrically controlled, in order to bring about the most perfect success and to meet the various requirements of railroad service. As in the inventions described

40 in those patents, I make use of valves locally applied to the various cars and under the direct control of the engineer through any suitable agency such for instance as electricity whose action upon the valves will be practically simultaneous throughout the train and not subject to the lagging which occurs when the operation of all is dependent upon the opening of a relief cock on the locomotive connected to a pipe leading through the train.

By my present invention I accomplish the 50 following results:

First. Should the electrical energy fail, by reason of breakage of the connections, or failure of the electrical power, be it supplied by primary battery, accumulators or a dynamo, 55 there would still remain a way in which the brakes could be operated partially, although with not so much success as when the electrical portion of the apparatus is in proper working order.

Second. The power can be applied at the same instant upon every car within the train and the release of that power is as nearly instantaneous as possible.

Third. The power to be applied is so completely within the control of the person applying it that the force may be graduated as circumstances may require.

Fourth. The brakes having been applied with such power as may have been stored 70 within the cylinders, if desirable that power may be largely increased by direct pressure.

Fifth. The arrangement of the apparatus is such that should the train become separated the brakes will be automatically applied by 75 the power within the various cylinders.

Sixth. The apparatus may be used as a direct pressure brake.

In the drawings I have shown but one cylinder with its accompanying accessories. Its 80 air supply and means for governing the same, so far as its action on the cylinder is concerned, are located within the engine cab, but it is obvious that the same arrangement, so far as the cylinder and accessories are concerned, may be duplicated as many times as it may be desirable, depending upon the number of cars it is desired to control.

I am aware that there are in existence automatic air brakes. I am also aware that there 90 are in existence direct pressure air brakes.

In the first class named there are many times when the brakes do not apply promptly, and when they have been applied they do not release promptly, rendering it necessary for 95 the cylinders to be emptied by sending some person or persons from car to car to open the vent cocks of the reservoirs by hand, thus

causing delay, and this class of brake does not, as a usual thing, admit of increasing the pressure while the brakes are still applied, beyond the pressure contained in the reservoir on the car at the instant of application.

In the second class of brakes I am aware that the pressure may be regulated by the amount of air which is passed to the piston head from the engine or compressor but should any portion of the train for any reason become detached, that portion which has become separated will continue to move with great momentum as the power to apply the brake ceases from the time that the detached portion becomes separated from the other portion of the train.

The aim of my invention is to avoid the objections incident to the above systems while at the same time securing the advantages of both.

In the accompanying drawings:—Figure 1, is a general plan of an apparatus embodying my invention, and shows the devices employed upon a single car only. Fig. 2, illustrates a modification in the arrangement of the circuit controller. Fig. 3, shows a modified arrangement of valves and magnets. Fig. 4, shows a modified arrangement of circuits and magnets. Fig. 5, illustrates a modification in which a single magnet is employed for operating two of the valves. Fig. 6, shows a modified arrangement of valve and magnet. Fig. 7, shows one way of arranging the controlling magnets for the brakes.

In the drawings A, represents a cylinder in which is a piston head W, affixed to a piston rod P, which rod in turn is attached to the brakes of a car. This piston rod is governed partially by spring S. It would not be necessary to employ such a spring to release the brake if the electrical energy and connecting circuits were always in proper condition because the engineer has within his control, as will presently appear, a means whereby he can admit of the passage of air into the cylinder in such a way as to force the piston head toward the center and thus release the brake; but in order to provide for contingencies which might arise, the spring is used as shown.

In the following description that side of the piston upon which the application of pressure from the air or other fluid serves to apply the brakes will be termed the rear of the piston and that side upon which the pressure of air or other fluid acts so as to release or unset the brakes will be termed the front of the piston.

V, indicates a valve of any suitable construction which is placed in a passage N, as indicated and between the rear of the piston and the pipe R, leading to the reservoir G, which is the source of air, gas or other fluid under pressure. The pipe R, is the usual air brake pipe extending through the train, and the reservoir G, is in the present instance supposed to be the air reservoir upon the locomotive and is supplied with air under press-

ure by any of the well known means known in the art.

The valve V, is controlled by an electro magnet X, which is in an electric circuit extending preferably to the locomotive where it is connected with a suitable circuit controller which may be actuated or operated for the purpose of governing the position of the valve V. Any form or kind of electro magnet known in the art and any form or kind of circuit controller known to electricians may be employed for the purpose of governing the valve.

In the present instance I have shown a form of electro magnet adapted to be worked by differences in the strength of the current on the circuit, produced preferably by the operation of a circuit controller which will make and break the circuit.

The electro magnet X, is in the present case arranged so as, when energized, to open the valve V, the latter being supported or carried by the armature of the magnet while a spring A⁴, applied to the armature tends to seat the valve.

The arrangement might be reversed as I have indicated in Fig. 6, but I prefer to employ the device shown in Fig. 1, because the valve will be automatically seated if the circuit should become interrupted as by parting of the train while to accomplish the same result with the arrangement shown in Fig. 6, it would ordinarily be necessary to employ a battery or other generator of electricity on the car. The magnet and valve are contained in a chamber B, and are suitably mounted therein in any desired mechanical fashion.

D, indicates a cock in the passage N, which cock is normally turned in position to allow free passage of air or other fluid when the electro magnetic arrangements are employed for controlling the brake.

In a by-pass around the valve as indicated is a second cock D', which is normally closed but may be turned to allow free passage of air around the valve V, in certain contingencies.

When the valve V, is opened by means of the electro magnet, air or gas under pressure may be admitted to the cylinder A, so as to fill the space at the rear of the piston W, and to apply the brakes unless there is a pressure at the front of the piston sufficient to hold the piston from movement.

If after the charging of the cylinder the counter pressure at the front of the piston should be relieved and the valve V, should be seated the brakes would obviously be applied by the pressure of the air contained in the cylinder at the rear of the piston and in the air tubes and spaces between the same and the valve.

In a passage T, leading from the front of the piston is a valve V², controlled by an electro magnet X², which devices may be of any desired description or arrangement and are electrically connected with a circuit controller on the locomotive. The valve V², is herein shown as controlled similarly to valve

V, that is to say a spring A³, applied to the armature carrying valve V², tends to seat the valve, while the electro magnet X², pulls on the armature in a direction to open the passage T, which latter connects, as does passage N, with the pipe R, or other source of air or gas under pressure. I prefer also to arrange the valve V², as shown so that the pressure of the air or gas in pipe T, will tend to assist the spring or other pressure in holding the valve seated when there is a relief of pressure at the front of the piston. A third valve V', is arranged to control an exit from passage T, or from cylinder A, through which air or gas may escape. Valve V', is in a chamber B', having one or more exits Q', to the outer air, and is controlled by any desired form of electro magnet governed by a circuit controller on the locomotive.

I prefer to arrange the electro magnet so that the valve will be seated to close the vent by the pull of the magnet upon its armature, while a retracting spring A², shall unseat the valve if the flow of current over the circuit in which the magnet is placed cease either by breakage of the electric conductor or by the operation of the circuit controller or key on the locomotive.

Leaving out of consideration for a moment the valve V², it will be seen that valve V', may be controlled so as to relieve the pressure at the front of the piston due to air or gas under pressure so as to permit the brake to be applied by the air or gas confined under pressure at the rear of the piston when the valve V, is closed as already explained. It is obvious also that the opening of the vent which allows escape of air from the front of the piston will take place in case the train parts because any current flowing in the magnet X', will cease, and the spring A², will unseat the valve V'.

In the passage T, is a cock D², which may be turned if desired to close said passage.

The magnets X', X², may be in the same or separate circuits as will be presently shown. In the diagram Fig. 1, they are shown included in the same circuit and the interruption of the circuit which will cause the vent V', to open will also cause the valve V², to close so that there shall be no waste or escape of air or gas from the pipe R, or other source of air or gas under pressure.

H, indicates a valve or cock on the locomotive under the control of the engineer or other party, which cock may be turned from the position shown so as to open communication between the pipe R, and the vent Q, thus allowing escape of air from the pipe R. When turned to produce such result the cock H, serves to cut off the flow of air or gas from the reservoir G.

The cock H, may be used without the electro magnetic devices in a similar way to a cock of a direct pressure air brake (as will be obvious) if the cocks D, D², be closed and the cock D', open, the magnet X', being at such

time cut out of circuit so that valve V', shall open the vent for escape of air from the front of the piston.

Circuit controllers suitable for use with the devices described are indicated at K, K'. In Fig. 1, they are shown as mounted on the handle of the cock H, but might be mounted and arranged in any suitable position.

The controller K, has, by means of a spring or other device, a bias which tends to keep the contacts open while the controller K', tends to keep its circuit closed. In the circuit of K, from a suitable generator of electricity M, B, is included the electro magnet X, for the valve V, while in the circuit of controller K', from the same or a separate source of electricity are included the electro magnets X', X², for valves V', V².

The mechanical construction of the circuit controllers may be indefinitely varied. In the present case the one circuit controller K, consists of a spring mounted on an insulating support attached to the handle and adapted to be pressed into contact with a stud also mounted upon but insulated from said handle. The circuit controller K', consists of a spring which tends to make contact with a bracket also mounted on the handle. The spring of K', is likewise suitably insulated and the devices are connected into circuit in the manner indicated.

The electric circuits are carried to the devices on the car through electric conductors insulated and combined in any desired manner as will be well understood by electricians. Electric couplings such as are employed in devices for signaling on trains by the agency of electricity may be used for completing the circuit between the cars and the couplings may, if desired, be arranged as has been heretofore proposed so as to automatically complete or break the circuits in case the electric couplings should be disconnected. These are details that may be indefinitely varied without departing from the principle of my invention.

The circuit controllers K, K', may be mounted in any desired position and may be of the ordinary button switch form such as indicated in Fig. 2.

The operation of the apparatus is as follows, assuming for the moment that the spring S, is not employed: Cock H, is first turned so as to bring pipe R, and outlet Q, into communication and by means of the circuit controller K, valve V, is opened so that any pressure existing behind the piston may be reduced to ordinary atmospheric pressure by escape of air through valve V, and pipe R. The valve V, is now closed by means of its circuit controller and the cock H, turned to the position shown so that air coming from the supply chamber G, will pass through pipe R, and valve V², (which is either normally open or is opened by means of its circuit controller) to the front of the piston, thus releasing the brake positively. In this opera-

tion the air is prevented from escaping at vent Q', by properly setting the valve V', by means of its circuit controller. When the brake has been sufficiently released by this means the key K, is again operated and valve V, is thus opened, thus allowing air to enter the cylinder A, at the rear of the piston where it is ready to act whenever the escape of air from the opposite side of the piston is permitted by means of valve V', and the valve V, is at such time in position to confine the air behind the piston. So long as it is not desirable to apply the brakes the pressure at the two sides of the piston is obviously substantially the same, and hence the piston does not move. During this time it is desirable to keep the valve V, open, though this is not necessary especially if a spring S, should be used to counteract any slight decrease of pressure behind the piston due to leakage.

Should it be desirable to apply the brakes, the valve V, if not already closed, is made to close by the operation of circuit controller K, and controller K', is operated so as to cause or permit valve V', to open (and also preferably, especially if the cock H, be not turned to cut off passage of air from G to R, to cause valve V², to shut). In this operation the shutting of valve V, and the opening of valve V', are obviously assisted by the pressure of air at the two ends of the cylinder. The brake is now applied by the pressure of air confined in the rear end of the cylinder A, and the passages or chambers between the same and the valve V. The escape of air might be also assisted (if valve V², should be dispensed with or combined with means whereby it could be opened at the same time with V') by turning cock H, to admit of direct communication between pipe R, and opening Q.

Should the engineer desire to increase the force with which the brakes are applied beyond that due to the pressure of the air confined at the rear of the piston while the valve V, is closed, he has it in his power to do so and to operate the brake as an ordinary direct pressure brake by simply actuating the circuit controller so as to open the valve V, thus opening the passage for air direct from chamber or reservoir G, with any pressure that may exist or be produced therein.

If before the first application of the brakes by the engineer as before described or during the time when the valve V, is opened for the purpose of increasing the pressure behind the piston, the electrical circuits should become destroyed by parting of the train the valve V, will immediately close thus retaining within the cylinder A, at the rear of the piston all of the power that had been placed there.

If the train should part before any application of the brakes the interruption of the circuit of X, and the closing of valve V, as just stated would be attended by the opening of valve V', owing to the interruption of

the circuit for X', by the breakage of the conductor including the same so that the pressure at the front of the piston would only be that of the spring S, (if such spring be used) and the brake would be applied by the pressure of the air confined at the rear of the piston. 7c

As before stated, the magnets may be connected into circuit in any desired way. Where a number of cars are employed the magnets may be arranged in series with one another or may be arranged in multiple arc connections as indicated in Fig. 7, after the manner well known to electricians. 80

In case through breakage upon any one car of the magnets or their immediate connections or through derangement of the mechanically controlled valves the apparatus should become inoperative as an electrically controlled brake it is only necessary to turn the cocks D, D', D², of that car so as to cut out the cylinder upon it leaving the apparatus upon the remaining cars to be controlled and operated in the manner already explained. 90

Fig. 3, illustrates a modification in which the valves V', V², are controlled by circuit closers K, K', as in Fig. 1; the action of the springs and magnets upon the valves being simply reversed. Valve V', is arranged so as to be closed by the action of a spring and to be opened by the pull of the magnet while valve V², requires the action of the magnet in order that it may be closed and is opened by the operation of a retracting spring or other device when it requires to be opened. Thus it will be seen that the circuit of magnets X, X', in this modification will need to be normally open circuits to leave the valves in their normal-positions as shown, instead of being normally closed circuits as in the construction shown in Fig. 1. This modification simply requires that the key governing valve V', should be closed instead of open in order to apply the brakes and that the key governing valve V², should be opened in order that the passage may be opened for the purpose of releasing the brake through pressure on the front of the piston. 105

I have hereinbefore described the magnets for valves V', V², as arranged in the same electrical circuit and controlled by the same key but they might be arranged in separate or independent circuits separately or independently controlled by keys K², K³, of any desired form as indicated in Fig. 4. 110

Where it is desired to operate the valves V', V², simultaneously they may be actuated by the same magnet instead of by separate magnets as indicated in Fig. 5, where the two valves are connected to the same armature and are arranged within a chamber B⁵, containing the operating magnet. The chamber is connected on the one hand with the front of the piston and on the other with the source of air or gas under pressure and the valves actuated by the magnet are arranged as shown to control a vent from said chamber communicating with the outer air and an inlet open-

ing through which the air or gas under pressure may flow from pipe T. When one valve is closed the other is open and a spring is suitably applied to normally tend to open the valve V', and close the valve V². When the magnet is excited the valve V', is closed and valve V², open but when the circuit of the magnet is broken the spring moves the armature in a direction to close valve V², and open valve V', with the effect already explained.

In case for any reason the main circuits of a train equipped with my apparatus should be destroyed or the electrical energy should fail the apparatus may be used as a direct pressure air brake apparatus by simply closing cocks D, D², and opening the cock D'. In this case the spring S, serves to take off the brakes when the valve H, is turned to relieve the pressure in pipe R, and when the valve is turned to open the passage from the reservoir G, to pipe R, the brakes are applied by the direct pressure of air at the rear of the piston.

In order to facilitate the releasing of the brake, the magnet chamber B, may be made large enough to admit of another magnet being placed within it, controlling a valve to an exit similar to Q', or another chamber containing a magnet controlling an exit valve may be placed in connection with the cylinder A, to perform this office. This is not shown in the drawings nor mentioned in the claims for the reason that the bleeding of the drum at each car is covered by patent issued to me (No. 361,089) bearing date of April 35 12, 1887.

A car fitted with a brake apparatus such as I have described may be included in a train fitted with any well known form of automatic air brake apparatus employing an auxiliary reservoir without interfering with the operation of either kind of brake. This may be done by closing the cocks D, D', and D², and using the cylinder A, as the regular piston cylinder for the automatic air brake, suitable connection from said cylinder being made to the ordinary reservoir, which is indicated in dotted lines at G', Fig. 1, as connected in the usual manner by valved pipes with pipe R, and said piston cylinder, the usual triple valve being used as at T, V.

While I have described some forms of magnets, circuit controllers, &c., I wish to be understood that I do not limit myself to specific forms inasmuch as my invention consists in the general combination and arrangements described and not in the specific forms of valves, cocks, magnets, circuit controllers, &c.

What I claim as my invention is—

1. The combination with the brake cylinder and connections therefor to the brake system, of a valve on the car in the passage between the source of pressure and the rear of the piston, a magnet controlling said valve, a controlling circuit for such magnet, a second valve independent of the first and having an

independent controlling magnet, and an escape passage or opening from the space at the opposite side of the piston controlled by said second valve, as and for the purpose described.

2. The combination with the brake cylinder, of a valve in the passage between the source of pressure and the rear of the piston, a controlling magnet for said valve, a valve controlling the escape of fluid from the front of the piston, a third valve independent of the first placed in the passage between the source of pressure and the front of the piston, and a magnet for controlling said third valve, as and for the purpose described.

3. The combination with a brake cylinder and a train pipe having a connection to the side of the piston upon which the pressure of air acts so as to release or unseat the brakes, of a valve in said connection and normally open, a second valve normally closed and controlling a vent or exhaust on the same side of the piston, and a magnet or magnets for opening the latter valve and at the same time closing the first named valve, as and for the purpose described.

4. The combination with the brake operating piston, of a valve on the car between the source of air or other fluid under pressure and that side of the piston upon which the pressure of air acts so as to release or unseat the brakes, an independent connection between a source of air or other fluid under pressure and the space at the opposite side of the piston, and a magnet for controlling the valve so as to permit ingress of fluid to hold the brakes off or to cut off the access of fluid when the brake is to be applied by the pressure at the opposite side of the piston.

5. The combination with the air brake cylinder A, of a valve on the car under the control of the engineer and controlling a passage connecting with the space at one side of the piston, an independent connection from a source of pressure to the space at the opposite side of the piston, an exhaust or vent valve connecting with the latter space, and a magnet controlling said valve for permitting the escape of fluid from the latter end of the cylinder, as and for the purpose described.

6. The combination with the brake cylinder, of an electrically controlled valve governing the passage of air or other fluid from the source of pressure to that side of the piston upon which pressure acts to take off the brake, said valve being exposed to pressure tending to seat and close it and thus preventing the passage of air to the cylinder to release the brakes, and an electro-magnet for unseating said valve, as and for the purpose described.

7. The combination with the air brake cylinder, of a passage leading to the engine from that end of the same in which pressure operates to take off the brake, a valve governing said passage on the car, a magnet for op-

erating said valve, and a controlled electric circuit leading from the car to the engine, as and for the purpose described.

8. The combination with an air brake operating cylinder having direct pressure connection to the supply pipe, of a magnetically controlled valve in said connection, and a by-pass around said valve.

9. The combination with the brake cylinder containing operating piston, of independent passages from front and rear of the piston respectively to a pressure supply pipe, spring S, for throwing the brakes off when both ends of the cylinder are connected to the pipe, and a magnetically controlled valve governing communication between the space at one end of the piston and the outer atmosphere, as and for the purpose described.

10. The combination with the brake cylinder and connections from the piston of such cylinder to the brake mechanism, of a valve in the passage between the rear of the piston and a pipe leading to the engine, a spring tending to close said valve, a magnet for opening the same, a second valve in a passage between the front of the piston and the outside air, a spring tending to close said valve, and an electro magnet for opening the same, as and for the purpose described.

30 11. The combination with an air brake cylinder and connections from the same to the brake mechanism, of two electro magnetically controlled valves, one in a passage leading to

the rear of the piston and the other in a passage leading from the front thereof to the outside air. 35

12. The combination with the brake cylinder, of two valves governing respectively the communication between the cylinder space in which pressure acts on the brake piston to unseat the brake and the source of pressure, and communication between the same space and the external atmosphere, an electro-magnet operating on the valve which controls the latter connection and normally tending to hold the same closed, and an electro-magnet operating on the first named valve or that which governs communication with the source of pressure, and normally tending to hold the same open, as and for the purpose described. 40 45 50

13. The combination with the train pipe and the brake cylinder, of a branch pipe connecting an end of the cylinder with the train pipe, a magnetically controlled valve in said branch pipe, a second branch pipe connecting to the opposite end of the cylinder and also containing a magnetically controlled valve, and a magnetically controlled valve governing communication between one end of the cylinder and the atmosphere. 55 60

Signed at Baltimore, in the State of Maryland, this 19th day of May, A. D. 1887.
